THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,786, dated February 21, 1882.

Application filed January 13, 1882. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed chiefly of the circular, rectangular, and cruciform figures A B C, and sprays of leaves and flowers diverging from said figures, as shown. Smaller figures of va-

rious forms are mingled with the leaves and flowers between the larger figures A B C.

I claim—

The design for a carpet, substantially as shown and described.

In testimony whereof I have signed my name to this specification, in the presence of two subscribing witnesses, this 3d day of January, 1882.

THOMAS J. STEARNS.
